UNITED STATES PATENT OFFICE.

WILLIAM DICHMANN, OF OSHKOSH, WISCONSIN.

MACHINE FOR SEWING HAY.

No. 834,369.

Specification of Letters Patent.

Patented Oct. 30, 1906.

Application filed May 1, 1905. Serial No. 258,375.

To all whom it may concern:

Be it known that I, WILLIAM DICHMANN, a citizen of the United States, residing at Oshkosh, in the county of Winnebago and State 5 of Wisconsin, have invented new and useful Improvements in Machines for Sewing Hay, of which the following is a specification.

This invention relates to improvements in machines for sewing coarse fibrous material— 10 such, for instance, as hay, grasses, or the like.

It is particularly adapted for sewing strands of hay laid parallel to form a continuous strip from which pieces may be cut, as in producing packing closures, such as bottle-wrappers or the like. 15

It is the object of the invention to make it possible to feed hay or like material into the machine spread comparatively evenly therein, so that the machine may hold and feed 20 the material automatically to the stitching-needles, the ends of the wisps of hay being trimmed to form the strip of a given width.

It is also the object of the invention to provide a stitching means which will bind the 25 material of which the strip is to be formed above and below, loopers and needles being employed and hooks for holding the loops of thread or cord or other material which may be employed for stitching the hay.

It is also a further object of the machine to 30 provide a means which shall automatically cut the strip after it has been stitched into proper lengths for forming various articles.

With these and other objects in view the 35 invention comprises certain novel constructions, combinations, and arrangements of parts, as will be hereinafter fully described and claimed.

In the accompanying drawings, Figure 1 is 40 a perspective view of my improved hay-sewing machine. Fig. 2 is a side elevation of the same. Fig. 3 is a vertical central longitudinal section through the sewing portion of the machine. Fig. 4 is a transverse vertical section through the upper portion of the machine, taken in front of the needle-operating mechanism. Fig. 5 is a detail sectional view 45 taken upon the line of the axis of the chain-actuating shaft located at one end of the machine, the said section being on an enlarged scale. Fig. 6 is an enlarged detail view, partially in section and partially in elevation, showing the edge-trimming cutters. Fig. 7 is an enlarged detail view showing in top 50 plan the chain-actuating sprocket mechan-

ism and the cutting mechanism for severing portions of the stitched strip of hay.

The machine forming the subject-matter of the present invention is provided with a suitable frame having supporting legs or standards 2 near the ends thereof and a top or bed 3, over which the material travels in being manipulated for forming a web or strip of fibrous material. Arranged transversely of the machine and near the central part 60 thereof is the main driving-shaft 5. This shaft is located below the bed 3 and supported by suitable bars and bracing-pieces in the frame. The ends of the shaft 5 project beyond the sides of the framing, and to one end 70 of the said shaft are secured fast and loose pulleys 4 for receiving power from any suitable source of energy to drive the machine. The shaft 5 extends across the machine in such a position that it can be utilized for operating the needles and loopers of the stitching mechanism, as well as the loop-holding hooks coöperating therewith. The said shaft is also provided with means by which the feeding mechanism for carrying the material through the machine is operated in proper relation to the movements of the stitching mechanism. The shaft 5 carries an eccentric 6 near one end, which is connected, by means of a pitman 7, with a rocking lever 8. The lever 8 is mounted at one end of a counter-shaft 9, which is located near one end of the machine and which is provided with the feed-driving mechanism. It is desirable to impart an intermittent movement 75 to the materials fed through the machine, and the lever 8 is therefore extended beyond the shaft 9, so as to carry a pawl 11, which engages the teeth of a ratchet-wheel 10. The said ratchet-wheel 10 is rigidly secured to the 80 shaft 9, so that any impulse imparted thereto will actuate the feed mechanism. As shown in Fig. 5, the lever 8 may be a double lever comprising a bar arranged on the opposite sides of the ratchet 10 and connected at its 85 ends by cross or tie bolts. The lever 8 is slotted, as at 12, and the pitman 7 engages a pin 13, which projects so as to extend into the slots 12 in the said lever 8. The pin 13 may be clamped at different positions in the slot 100 12 for varying the throw of the lever and shortening or lengthening the extent to which the feed mechanism is moved at every oscillation of the lever 8.

The means for carrying and feeding the 110

fibrous material or hay through the machine comprises a plurality of sprocket-chains 15. I have shown three of such sprocket-chains, although of course a less or greater number 5 can be employed, as preferred. Three chains, however, perform the desired duty with sufficient facility, and I will proceed with the description of the chains as shown in the drawings. The chains may be arranged at 10 equal distances from each other, or some may be closer together than others. As shown in the drawings, the chains are equidistant from each other and engage at one end of the machine a series of sprocket-wheels 14, which 15 are rigidly secured upon the shaft 9, so as to turn therewith. The upper stretches or laps of the chains extend along approximately even with the upper surface of the frame-bed 3 to the opposite end of the machine, where 20 the said chains pass around sprocket-wheels 16, secured to the transverse shaft 17. The chains thence pass downwardly beneath the operating mechanism mounted upon the central portion of the machine and back to the 25 actuating sprocket-wheels 14. The lower lap or stretch of each of the chains is engaged by a sprocket-wheel 18, which is carried on a shaft by an arm or frame 18^a, pivoted to the under side of the frame. The weight of these 30 sprocket-wheels and the arms which carry them act as tighteners for the chain and take up any slack therein automatically. The upper stretches or laps of the chain travel upon longitudinally-arranged ways or 35 supports 19. The chains are thus prevented from sagging in their position for feeding and supporting the hay as it is carried to the needles. At the front end of the machine a feed-plate 20 is provided, which is made of 40 sufficient width to permit of the hay being laid thereon and spread out preparatory to pushing it upon the feed-chains 15. This plate preferably extends above the sprocket-wheel 16 at the front end of the machine. 45 The feeding of the chains accomplished by the action of the pawl 11 in connection with the ratchet 10 is such as to cause the material to travel from the feed-plate 20 toward and beneath the stitching-needles at the center of 50 the machine. As the material approaches the stitching-needles it is desirable to hold the same more or less firmly upon the feeding-chains, and for this purpose the material is caused to pass beneath the arms or longitudinally-arranged bars 21, having upturned ends. 55 These bars are preferably pivoted at 27 to an upper pressure-frame, which is arranged to the rear thereof. In this manner the front ends of the bars are free to rise and fall of their 60 own weight in pressing upon the fibrous material fed to the stitching mechanism.

To insure a proper holding of the fibers of the hay as the same are being stitched, I employ a pressure or tension frame, which extends beyond the stitching-needles to the front

and rear. This frame is made up of longitudinally-arranged bars 22, preferably located directly above the outer feed-chains 15. Cross-bars 23 extend from one pressure-bar 22 to the other transversely of the machine and loosely engage vertical pins or studs 25. These studs or pins 25 are provided with heads at their upper ends, and springs 26 are arranged upon the said pins or studs and shouldered against the heads 25, their lower ends bearing against the upper surfaces of the transverse bars 23. The whole frame thus formed is normally pressed downwardly by the action of the springs 26. The material as it approaches the frame is properly guided 80 beneath the same by the pivoted arms 21, heretofore described. In addition to the outer bars of the frame I also secure to the cross-bars 22 an intermediate pressure-bar 24^a, which is formed with an upturned end at 85 the front, so that the fibrous materials or hay will easily pass beneath the same. This intermediate pressure-bar 24^a is preferably located in line with and directly above the intermediate feed-chain 15. By this mechanism it will be seen that the fibers or strands of hay which have been spread upon the chains can be firmly held at their ends upon each side of the machine when the stitching operation is performed. 95

About centrally of the machine is mounted the stitching mechanism, which in order to properly draw the threads or twine about the strands of the hay is provided with needles and loopers and also with auxiliary loop-holding mechanism. In stitching hay or fibrous material into a continuous strip—such, for instance, as usual in forming wrappers for bottles or other articles—it is needful to have a plurality of stitches located near the edges 100 of the strip, and at intermediate points, if desired. For the sake of description and illustration I have shown the machine in the accompanying drawings provided with two sets of needles arranged to stitch along adjacent to the outer edges of the completed web. 105

Rising from the frame-bed 3 are side brackets 3^a, which are rigidly secured and transversely arranged upon the cross-head 3^b. Upon one face of the cross-head 3^b is secured 115 guiding means for the vertically-operable needle-carrying bars 52. These needle-bars are connected and reciprocated by a cross-head 51, which is connected by means of a pitman 49, pivotally secured thereto by a 120 pin 50, with a wrist-pin 48 projecting from the disk 47. The disk 47 is actuated by a shaft 46, which is carried in suitable bearings upon the cross-plate 3^b. The said shaft 46 is rocked by means of a slotted arm 41, 125 which projects from a second rock-shaft 40, also mounted in bearings upon the cross-plate 3^b. The slot formed in the arm 41 is engaged by a bearing-block 43, which is secured upon a wrist-pin 44, carried by an arm 130

45, which projects from the shaft 46. The different radial movements of arm 41 and the arm 45 are thus accommodated in imparting movement from the shaft 40 to the shaft 46. 5 The shaft 40 is rocked by means of an arm 39, which is connected by a pitman 38 with the wrist-pin carried by the disk 37. The said disk 37 is rigidly secured to the actuating-shaft 5. The radial distance of the wrist-pin on the disk 37 is smaller than the radial distance from the center of the shaft 40 to the end of the lever 39, and a complete rotation of the disk 37 will thus operate to produce only a rocking movement in the shaft 10 40. The needle-bars 52 carry needles 53, which are provided with closed eyes and project from the bars a sufficient distance to pass through and below the fabric or web being formed for carrying the loops of thread 15 or cords to the loopers, as will be hereinafter fully explained.

Operating in conjunction with the needles are loopers 60, which are adjustably secured to the upper ends of rocking arms 55 by means 20 of adjustable clamps 61. The arms 55 are carried by sleeves pivotally mounted upon a shaft 56, which extends transversely of the machine and is supported in suitable standards rising from the frame thereof. Actuating-arms 55^a project downwardly from the said sleeve and extend to points in close proximity to the actuating-cams 54, which are rigidly carried by the shaft 5. The arms 55^a carry antifriction-rollers which run upon 25 the peripheries of the cams 54. The arms 55^a are held against the said cams by springs 59. The cams 54 are provided with depressed portions at one point in their peripheries, into which the rollers of the arms 55^a drop 30 for carrying the loopers 60 forward to catch the loops of the needles. The continued rotation of the cams cause the retracting of the needles at the proper time.

Coöperating with the loopers are hooks 64, 45 which are carried by the outer free ends of arms 70, which are rigidly secured to the shafts 68. The shafts 68 are mounted at their ends in brackets which rise from the frame, and the said shafts are preferably so 50 held as to be capable of rocking. Arms 67 are also secured to the said shafts 68 and project a sufficient distance to engage the peripheries of cams 65, rigidly secured to the shaft 5. The ends of the arms 67 are provided with antifriction-rollers 66, which run 55 upon the peripheries of the said cams 65. The said rollers are kept in engagement with the cams by a spring 74. The cams 65 are formed with recesses at 75, arranged between the periphery of the cam at a short 60 distance from the center of movement and a portion of the cam which is at a greater radial distance from the center of movement. As each cam 65 rotates, the rollers 66 gradually descend into the recess 75 and will be

quickly raised therefrom to the highest part of the peripheral path. The hooks 64 have bearings in the outer ends of the arms 70, and each of said hooks is provided with a crank-arm 71, which is provided with a 70 wrist-pin 72, extending therefrom and engaging a slotted projection 73, which extends downwardly from the framing. The wrist-pin 72 may be provided with antifriction-rollers 72^a for engaging the bifurcated 75 extensions 73. Since the crank 71 is rigidly secured to the shank of the hook 64 and since the wrist-pin 72 engages the fixed bifurcated projection, it will be evident that a rocking movement given to the arm 70 will cause the 80 hook to be turned over or rotated about its longitudinal axis. In this manner the hook may be thrown into the loop formed by the looper and temporarily hold it, said hook releasing the loop after the stitch is completed. Before the material which has passed to the stitching mechanism reaches it it is trimmed to a given length, and for this purpose I employ rotary cutters 35 and 36, there being a pair of said cutters upon 90 each side of the machine, as clearly shown in Fig. 6. The cutters 35 are rigidly mounted upon a shaft 30, which extends across the framing of the machine, and one end of said shaft is provided with a sprocket-wheel 95 29, which is connected by a sprocket-chain 31 with a sprocket-wheel 28 on the shaft 5. The shaft 30 is thus rotated in conjunction with the operation of the shaft 5. The cutters 36 are carried by a shaft 34, parallel with the 100 shaft 30 and preferably mounted directly beneath it, and motion is transmitted from the shaft 30 to a shaft 34 by intermeshing gears 32 and 33, secured to the ends of said shafts. The cutters 35 and 36 are oppositely beveled, 105 their cutting edges being brought together to make a shearing cut, as clearly illustrated in Fig. 6. These cutters 35 and 36 are also preferably notched, as shown in Fig. 3, which notching of the cutters is found to assist in 110 the drawing forward and feeding of the material past the cutters.

At the end of the machine a cutting mechanism of a different type is employed and which is capable of cutting off the stitched material in given lengths. This end cutting mechanism comprises a shaft 80, mounted in journals at the end of the machine and carrying cutter-heads joined by a cutting-knife 77. This knife 77 operates in conjunction with a 115 fixed knife 76, which is secured to the end rail of the frame. The knife 77 is rotated by means of gears 78 and 79, which intermesh, one of said gears 78 being rigidly fastened to the shaft 9, while the other gear 79 is rigidly secured to the shaft 80. The knife 77 is thus intermittently rotated by the action of the shaft 9, which is operated by the ratchet 10. The knife 77 is held in its fixed position by clamping-screws 77^a. By loosening these 120

130

screws and turning said screws 77^b the knife may be accurately adjusted to make a shear cut in conjunction with the knife 76. Although the knife 77 is carried in an arc of 5 small diameter, it is only operated by an intermittent movement received from the shaft 9, and thus the piece of stitched material which is cut off will be amply long for forming bottle-wrappers or other desired articles.

10 In the operation of the machine the hay, straw, grass, or other fibrous material is spread upon the belt 20 so that the strands thereof extend transversely of the machine, and the material is then pushed from the belt 15 upon the chains 15. The material will be carried beneath the movable ends of the bars 21 and then beneath the pressure-frame formed by the bars 22. The material will first encounter the trimming-knives 35 and 20 36, which being connected with the shaft 5 are continuously rotated, trimming the fibers to a proper length before they are passed to the stitching mechanism. After passing the knives the fibrous material is carried to the 25 needles for forming stitches near each edge of the line of fibrous material. The needles 53 are supplied with yarn or cord 62^a, which is lead from a bobbin 62, mounted upon the upper edge of the cross-plate 3^b, the strands of 30 thread, yarn, or cord being carried upwardly from the bobbins to the guides 62^b and thence downwardly through guides 52^a carried by the needle-bars, and thence through guide-eyes 52^b, secured to the face of the cross-plate 3^b. The material is then lead to the 35 closed eyes of the needles 53. The loopers 60 are supplied with thread or cord from bobbins 63, mounted upon the lower portion of the frame, the said thread or cord being lead 40 upwardly and through apertures formed in the frame and thence to the loopers. Any desired tension mechanism may be used for controlling the feed of the threads or cords to the stitching mechanism. As the material 45 passes between the needles and loopers the needles move downwardly through the grass or fiber, carrying a loop of cord with them. The needles to reach their lowest points are slightly raised again through the action of the 50 disk 47, which carries the wrist-pin 48 slightly beyond the lower dead-center of its movement. This causes the formation of a more permanent loop beneath the grass or hay and insures the engaging of said loops by 55 the loopers. At this time the cams 54 operate to throw the loopers 60 upwardly and through the loops formed by the needles. The points of the loopers 60 are preferably slightly bent downwardly, as shown in Fig. 3, 60 so that the loops of the needles will be held by the loopers while the needles are being raised. The loopers in passing through the loops carry a loop of the lower cord with them and hold them in position to be engaged by the rocking 65 hooks 64. The relative positions of the cams

65 and 54 are such that the hooks will at this time be thrown downwardly into the loops which were brought in by the loopers. After the hooks have engaged the lower loops the loopers quickly return to their outermost positions, and at the same time the upper needles descend again, pulling the upper thread through the tension mechanism sufficiently to permit of the upper loop being extended far enough to form the proper stitch, after which the needle returns. The hook 64 retains the lower loop until the needle descends through the lower loop, after which the hook is rocked, quickly releasing the loop. The operation is repeated for each stitch. The machine 70 is generally used in sewing marsh-hay into packing-strips in two or more series of lock chain-strokes. In sewing such coarse material as hay or the like it is desirable to use a comparatively coarse thread or cord, and the 75 action of the needles and loopers, together with the holding-hook, is such as to be admirably adapted for using such kinds of coarse material. The machine is positive in its action, and the securing of the cams and 80 the other needle-operating mechanism to a single driving-shaft makes it possible to exactly and accurately time the movement of the needles and loopers and the hooks with respect to each other. The strips of packing 85 material can be in any suitable lengths (the trimming-knives to be set the proper distance apart to cut the material in the length desired) for packing various articles—such, for instance, as bottles or similar closures. 90 Of course it will be understood that the machine can be employed for stitching other articles, as desired.

Having thus fully described my invention, what I claim as new, and desire to secure by 95 Letters Patent, is—

1. A machine of the class described, comprising a stitching mechanism, endless means for carrying fibers arranged in approximately parallel arrangement, means for exerting a pressure upon the said fibrous material, pivoted guide means for leading the material beneath the pressure means and means for giving the feeding mechanism an intermittent movement.

2. A fibrous-material-stitching machine comprising a longitudinal supporting-frame, an endless traveling conveyer moving therewith, a spring-pressed frame arranged above said conveyer for pressing the material 100 against it, stitching-needles mounted above the said conveyer, thread-loopers arranged below the conveyer and adjacent to the points occupied by the needles when lowered, and rocking hooks operating in conjunction 105 with the loopers.

3. A machine for stitching fibrous material, comprising traveling means for carrying the material, stitching-needles operating above the conveyer so as to engage the 110

fibrous material as it is fed to the stitching mechanism, loopers below the said needles, a rock-shaft for actuating the loopers, loop-holding hooks coöperating with the loopers, rock-shafts for carrying the hooks, and a common shaft provided with means for operating all of said rock-shafts in proper timed relation to each other.

4. A machine for stitching fibrous material, comprising means for carrying the material to the stitching mechanism, guiding and pressing devices mounted above the same stitching-needles arranged to engage the material, loopers for engaging the thread carried by the needles, arms carrying said loopers, rock-shafts carrying the arms, cams for actuating the loopers in proper relation to the movement of the stitching-needles and loop-holding hooks cooperating with the loopers.

5. A machine for stitching fibrous material, comprising a traveling conveyer, stitching-needles capable of engaging the material, loopers, loop-holding hooks, rock-shafts carrying the loopers and the hooks, cams for operating the looper rock-shaft and the shafts of the hooks in proper timed relation, and a common rock-shaft carrying the said cams.

30 6. A mechanism for stitching fibers into a continuous strip comprising a supporting-frame, a traveling conveyer moving over the same, a plurality of stitching-needles mounted above the conveyer, a plurality of oscillating loopers arranged below the conveyer, rocking hooks operating adjacent to the loopers and in conjunction therewith, and fixed means for causing the rocking of the hooks when the said hooks are moved bodily 40 from side to side.

7. A fibrous stitching machine for forming elongated strips comprising a supporting-frame, longitudinally-traveling endless conveyers for carrying the fibrous material over the frame, reciprocating needles mounted above the conveyer, loopers mounted below the conveyer, rocking hooks also mounted below the conveyer and having arms projecting therefrom, fixed means engaging 45 said arms, and movable means carrying the needles, said fixed means causing the rocking of the hooks when the said movable means is operated.

8. A wrapper-stitching mechanism, comprising a frame, a feeding mechanism mounted thereon, a stitching mechanism and a pressure-frame mounted above the feeding mechanism comprising longitudinal bars, and cross connecting-bars, springs engaging the 55 cross-bars for forcing the frame downwardly with a yielding pressure, pins carrying the said springs and having heads as a bearing therefor.

9. A mechanism of the class described, 60 comprising a frame, an endless conveyer

traveling over the bed-plate of said frame, a pressure-frame arranged above the conveyer having pivoted receiving end portions, and spring-actuated means for forcing the frame downwardly upon material carried by the 70 conveyer.

10. A machine for stitching fibrous material into strips comprising an elongated traveling conveyer, a needle stitching mechanism mounted above the same, oscillating 75 loopers mounted below the same and co-operating with the stitching mechanism, oscillating arms moving at right angles to the oscillating loopers, rocking shafts carried in the free ends of said arms and having 80 thread-engaging hooks at their ends, arms projecting from said rock device, and fixed guides engaging said arms and causing the rocking of the said rock device when the oscillating arms are moved from side to side. 85

11. A machine for stitching fibrous material into strips, comprising a frame having longitudinally-arranged supporting-bars, endless chains traveling over and resting upon the said supporting-bars, sprocket-wheels supporting the said chains, a ratchet mechanism for driving the chains with an intermittent feed, an assembling-plate upon which the fibrous material may be arranged preparatory to pushing it upon the traveling 95 chains, a pressure-frame arranged to engage the fibrous material upon the top and a stitching mechanism for stitching the material into a strip, springs engaging the frame at suitable points for exerting a yielding pressure upon the same, the pressure-frame holding the material properly while the stitching mechanism is operating upon it. 100

12. A machine for stitching fibrous material, comprising a traveling conveyer, reciprocating stitching-needles, rocking loopers, a rock-shaft carrying said loopers, loop-holding hooks having cranks formed thereon, means for loosely engaging the cranks, rock-shafts carrying the said hooks and moving them with respect to the crank-engaging 105 means and cams for operating the stitching-needles, loopers and hooks. 110

13. A machine for stitching fibrous materials, comprising a conveying mechanism, 115 stitching-needles arranged above the material, looping-needles arranged below the same, levers for actuating the looping-needles, cams for engaging the levers and rocking them, rocking hooks coöperating with the looping-needles, rock-shafts carrying the same, arms projecting therefrom, cams for engaging said arms and rocking the hooks and a rotating shaft for actuating all of the 120 said cams. 125

14. A machine for producing packing material from fibrous hay or the like, comprising a traveling conveyer for feeding the material to the machine, a stitching mechanism, means for moving the material intermittently be- 130

tween the stitches, a rotating cutter means for connecting the said cutter with the intermittent feed-actuating mechanism, comprising gearing and means for actuating the 5 stitching mechanism in correspondence with the feed of the conveyer.

15. A machine for producing packing-strips from fibrous material comprising a conveyer, a stitching mechanism, reciprocating needles, a rock-shaft for operating the needles, a crank-arm for actuating the rock-shaft, a rock-lever having a movable engagement with the crank-arm, a pitman for rocking the said rock-lever, a disk connected with 10 the pitman, and a shaft for actuating the said disk.

16. A machine for producing a web of fibrous packing material, comprising a feeding mechanism, a stitching mechanism made 20 up of reciprocating needles, rocking needles, rocking hooks mounted adjacent to the rocking needles, a crank-arm formed upon the said rocking hooks, fixed guides engaging the said crank-arms, arms for moving the hooks 25 with respect to the said guides and producing their rocking action, and cams for rocking the said arms.

17. A machine for stitching fibrous packing-strips, comprising a frame, a traveling 30 conveyer and an elongated pressure-frame engaging the material, stitching-needles engaging the material, loopers operating beneath the upper portion of the conveyer for forming loops, a rock-shaft having laterally-

projecting arms for carrying the said loopers, 35 the loop-holding hooks having crank-shaped end portions, arms carrying said hooks, guides engaging the crank-shaped end portions and causing the turning of the hooks as they are carried back and forth by the said 40 arms, rock-shafts carrying the said arms and cams for rocking the said shafts and causing a proper timed operation of parts with respect to each other.

18. A mechanism for stitching fibrous material, comprising feeding means, stitching means made up of upper reciprocating needles, lower bent looping-needles, rocking arms carrying the looping-needles, cams having depressed portions in their peripheries for 45 rocking said arms, means for holding the arms against the said cams, rocking hooks coöperating with the looping-needles, arms for rocking said hooks, cam-engaging arms connected with said rocking arms, cams for 50 engaging the actuating-arms, said cams having depressed portions in their peripheries, means for holding the actuating-arms in engagement with the said cams and a common 55 actuating-shaft carrying the said cams. 60

In testimony whereof I have hereunto set my hand in the presence of two subscribing witnesses.

WILLIAM DICHMANN.
